(57) **CLAIM**

The ornamental design for a seating and kneeling stool, as shown and described.

DESCRIPTION

FIG. 1 is a perspective view of a seating and kneeling stool showing my new design;

FIG. 2 is a front view thereof;

FIG. 3 is a right side view thereof;

FIG. 4 is a left side view thereof;

FIG. 5 is a rear view thereof;

FIG. 6 is a top view thereof;

FIG. 7 is a bottom view thereof;

FIG. 8 is an exploded perspective view thereof;

FIG. 9 is a perspective view of the seating and kneeling stool in a second configuration wherein the handle is in a collapsed state;

FIG. 10 is a perspective view in a third configuration wherein the legs are in a collapsed state; and,

FIG. 11 is a perspective view in a fourth configuration wherein both the handles and legs are shown in a collapsed state.
